US0D1076506S

(12) **United States Design Patent** (10) **Patent No.:** **US D1,076,506 S**
(45) **Date of Patent:** **** May 27, 2025**

(54) **SHELF**

(71) Applicant: **Zhejiang Cheng's Plastic Products Co., Ltd.**, Jinhua (CN)

(72) Inventor: **Bo Cheng**, Nanchang (CN)

(73) Assignee: **Zhejiang Cheng's Plastic Products Co., Ltd.**, Jinhua (CN)

(**) Term: **15 Years**

(21) Appl. No.: **29/967,370**

(22) Filed: **Oct. 9, 2024**

(51) **LOC (15) Cl.** **06-04**

(52) **U.S. Cl.**

USPC **D6/574**

(58) **Field of Classification Search**

USPC D6/574, 518-524, 548-550; D8/300, D8/303, 315-321, 349, 354, 363, 373, D8/380

CPC B62B 3/00; B62B 3/002; B62B 3/005; B62B 2501/067

CLAIM

The ornamental design for a shelf, as shown and described.

DESCRIPTION

FIG. 1 is a front perspective view of a shelf, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the drawings illustrate the portions of the shelf, which form no part of the claimed design.

1 Claim, 8 Drawing Sheets
